UNITED STATES PATENT OFFICE.

THOMAS H. WILLIAMS, OF JERSEY CITY, NEW JERSEY, ASSIGNOR TO HIMSELF AND SAMUEL D. TOMPKINS, OF SAME PLACE.

DESIGN FOR A RADIATOR.

SPECIFICATION forming part of Design No. 19,312, dated September 10, 1889.

Application filed July 10, 1889. Serial No. 317,068. Term of patent 14 years.

To all whom it may concern:

Be it known that I, THOMAS H. WILLIAMS, of Jersey City, in the county of Hudson and State of New Jersey, have invented and produced a new and original Design for Radiators, of which the following is a specification.

My original design relates to the shape and configuration of the radiator pipes or sections in sectional shape and in outline.

- In the drawings, Figure 1 is an elevation (partially broken) of my radiator, showing the outline, shape, and configuration; and Fig. 2 is a sectional plan of the same at the line $x-x$ of Fig. 1.
- 5 The leading feature of my design is the sectional shape and configuration of the radiator pipes or sections, the center portion A of which is a hollow, oblate hexagon, having parallel portions or faces $a-a'$ and $b-b'$ and parallel ends $c-c'$. The outer portions B of the radiator pipes or sections are in shape hollow, half-oblite hexagons on the sides adjoining the central portion A, with flat portions or faces $d-d'$, the portions a and d , b and d' , and the 5 portions a' and d' b' and d being parallel, and

there are raised beaded central parts at $e-e'$. The outer portions of B are angular in shape, with converging and partially-curved surfaces, as at $f-f'$, with flattened parts, having a beaded edge at g .

The outline shape of the radiator-section, Fig 1, is curved at the upper end h with a plain surface at i . The lower portion has a curved and inclined outline at the bead k . The supports V have an inner curved outline 35 and an outer irregular contour of scallops and curves.

I claim as my invention—

The design of the shape and configuration of the radiator-section herein shown and described, the same consisting of the design of the hollow portions A B, of the sectional configuration shown, the upper portions $h-i$, and the bead k , substantially as set forth.

Signed by me this 6th day of July, A. D. 1889. 45

THOS. H. WILLIAMS.
